(57) **CLAIM**

The ornamental design for a water generation panel as shown and described.

DESCRIPTION

FIG. 1 is a perspective view of a first embodiment of a water generation panel;

FIG. 2 is a top view of the water generation panel of FIG. 1;

FIG. 3 is a front view of the water generation panel of FIG. 1;

FIG. 4 is a back view of the water generation panel of FIG. 1;

FIG. 5 is a right side view of the water generation panel of FIG. 1;

FIG. 6 is a left side view of the water generation panel of FIG. 1;

FIG. 7 is a bottom view of the water generation panel of FIG. 1;

FIG. 8 is a perspective view of a second embodiment of a water generation panel;

FIG. 9 is a top view of the water generation panel of FIG. 8;

FIG. 10 is a front view of the water generation panel of FIG. 8;

FIG. 11 is a back view of the water generation panel of FIG. 8;

FIG. 12 is a right side view of the water generation panel of FIG. 8;

FIG. 13 is a left side view of the water generation panel of FIG. 8; and,

FIG. 14 is a bottom view of the water generation panel of FIG. 8.

The broken lines depict portions of the water generation panel that form no part of the claimed design.

Off Grid Atmospheric Water Generator, May 31, 2016, YouTube, site visited Jan. 27, 2025: <https://www.youtube.com/watch?v=HMe7m56jMlg> (Year: 2016).*

Non-Final Office Action dated Jan. 17, 2020 in U.S. Appl. No. 15/528,366.

Final Office Action dated Apr. 27, 2020 in U.S. Appl. No. 15/528,366.

Notice of Allowance dated Jun. 19, 2020 in U.S. Appl. No. 15/528,366.

Notice of Allowance dated Mar. 1, 2019 in U.S. Appl. No. 15/600,046.

Non-Final Office Action dated Feb. 5, 2019 in U.S. Appl. No. 15/482,104.

Notice of Allowance dated Jun. 27, 2019 in U.S. Appl. No. 15/482,104.
